UNITED STATES PATENT OFFICE

146,196

DESIGN FOR A WHATNOT

David Sorcher, Brooklyn, N. Y.

Application February 6, 1946, Serial No. 126,302

Term of patent 3½ years

(Cl. D33—3)

To all whom it may concern:

Be it known that I, David Sorcher, a citizen of the United States, residing at Brooklyn, in the State of New York, have invented a new, original, and ornamental Design for a Whatnot, of which the following is a specification, reference being had to the accompanying drawings, forming part thereof.

In the drawings:

Fig. 1 is a front elevational view of a whatnot illustrating the new design;

Fig. 2 is an end elevational view;

Fig. 3 is a rear elevational view; and

Fig. 4 is a plan view.

I claim:

The ornamental design for a whatnot, as shown.

DAVID SORCHER.
